UNITED STATES PATENT OFFICE.

OSCAR A. ROSS, OF ROCHESTER, NEW YORK.

DESIGN FOR A RELAY-CASING.

44,323.

Specification for Design.

Patented July 8, 1913.

Application filed May 1, 1913. Serial No. 764,939. Term of patent 14 years.

To all whom it may concern:

Be it known that I, OSCAR A. ROSS, a citizen of the United States, and a resident of the city of Rochester, in the county of Monroe and State of New York, have invented a new, original, and ornamental Design for a Relay-Casing, of which the following is a specification, reference being had to the accompanying drawing forming part thereof.

The figure is a perspective view of a relay casing, showing my new design.

I claim:

The ornamental design for a relay casing, as shown.

OSCAR A. ROSS.

Witnesses:

LILLIAN L. PHILLIPS,
SHERMAN A. BENEDICT.
